UNITED STATES PATENT OFFICE

ANTONI WILHELM KRUL, OF THE HAGUE, NETHERLANDS

GAS HEATED HOT WATER RADIATOR

Application filed November 20, 1930, Serial No. 497,015, and in the Netherlands October 11, 1929.

The invention relates to a hot-water radiator adapted to be gas heated and has for its object to so construct this radiator that a large heat-generation requires but a small 5 gas-consumption.

The invention consists in that in a hot water radiator use is made of a gas burner, the body of which is inserted in a connection between the lower ends of two groups of radiator elements in such a manner that the said connection at the burner body forms a water jacket which is integral with the burner body itself. By reason of the fact that the burner flames rapidly bring the burner body 15 and its water jacket to a high temperature and that by heat conduction through the metal of the connection the lower ends of the radiator elements will also be intensively heated, an increased water circulation is produced. This circulation can be maintained 20 by means of a small flame and consequently a small gas consumption. A greater part of the heat generated by the burner than in hot water radiators of the known type comprising an independent burner, is now utilized 25 for heating the lower portion of the radiator elements, which is most favourable for the circulation.

In order to facilitate the manufacture and 30 to allow for variation of the heat capacity of the radiators in a simple manner, according to the invention, a double walled water chamber with burner body integral therewith may be constructed as an independent unit 35 which is provided at either side with connections to which, in accordance with the heat capacity of the radiator desired, one or more radiator elements may be connected. In a radiator the bottom of the said unit then constitutes the above mentioned connection 40 which at the place of the burner body forms a water jacket that is integral with the burner body itself. In the said double walled water chamber the combustion gases ascend, 45 the path of which may be lengthened by means of a partition which compels the gases to first flow upwards and then downwards along the other side of the partition towards the outlet. In one of the walls of the water 50 chamber an aperture, adapted to be closed,

may further be provided so that the burner table may be removed for cleaning purposes or the like. The burner table forms in the usual manner a separate piece adapted to be positioned on the burner body into which it 55 may extend down into the mixture chamber with a pocket shaped extension.

The invention will be more fully understood with reference to the accompanying drawings illustrating it by way of example. 60

Fig. 1 is a side elevation partly in section of a hot water radiator with gas burner according to the invention.

Fig. 2 is on a larger scale a vertical section of the gas burner with water jacket and connections separately. 65

Fig. 3 is a horizontal section on the line III—III in Fig. 2.

Fig. 4 is a section on the line IV—IV in Fig. 5 of a double walled water chamber with 70 gas burner constructed as a unit in accordance with the invention.

Fig. 5 is a section perpendicular to Fig. 1.

Fig. 6 is a horizontal section on the line VI—VI in Fig. 5. 75

The apparatus according to Fig. 1 comprises a gas burner 1 which as shown in Figs. 2 and 3 is provided with a burner table 2 having the usual apertures 3 and an extension 4, integral with the burner table 2, closed 80 at the bottom and of tubular formation. This extension is located in a mixture chamber 5 which is confined by the inner wall 6 of a water jacket 7, the outer wall of which is denoted by 8. 85

The gas and air mixture is supplied through a pipe 9 to the mixture chamber 5. The water jacket 7 is connected by passages 10 and 11 at its sides to the lower ends of two groups of radiator elements each comprising four 90 elements indicated by 12 and 13. The connection is established by means of left and right handed screw threads 14 and 15. The radiator elements 12 and 13 are at the top interconnected by a connecting piece 16 which 95 to this end may also be provided at its ends with left and right handed screw thread. The connecting piece 16 is centrally connected by a downwardly directed passage 17 to the water space of a double walled bell-shaped 100

container 18, which at the bottom at either side of the burner 1 is connected by passages 19, 20 to the passages 10 and 11, communicating with the water jacket 7. The container 18 is located centrally above the burner 1 so that the combustion gases will ascend in the interior space 21 of the container, from which space they are discharged through discharge openings 22 located at different heights and 10 enter a cap 23 enclosing the container 18 and having a discharge 24 to a stack not shown. 25 indicates a water storage tank mounted on the connecting piece 16 and connected to the passage 11 by a conduit 26.

15 In the tank 25 an expansion tube 28 is arranged the upper end of which is bent in U-shape. When the gas burner 1 has been lighted and after the water jacket and thereby the connecting conduits and the lower 20 ends of the radiator elements have been heated to a high temperature by heat conduction, a strong circulation from the groups of radiator elements 12, 13 through the passages 19, 20 into the water space of the container 18, 25 through the passage 17 and the connections 16 and then into the upper ends of the radiator elements 12, 13 will be maintained. The combustion gases are also utilized for the heating of the container 18. Should the 30 temperature become too high and steam be produced in the radiator, then the steam can escape from the connecting piece 16 through the tube 28 into the water tank 25 and fresh water may be supplied to the connecting piece 35 11 through the conduit 26.

In Figs. 4-6 an element is shown by way of example, which forms an individual unit and is adapted to be connected at either side to one or more radiator elements. It consists 40 of a double walled water chamber 29, the bottom of which is integral with a burner body 30. The chamber is provided at either side at the top and at the bottom with pipe sections or tubular pieces 31 for connecting it 45 to one or more radiator elements. In this embodiment the burner body is again provided with a water jacket which is in communication with the lower connections 31. The interior space of the chamber 29 is heated by 50 the combustion gases which by a partition 32 are compelled to first flow upwardly in the space 33 and then downwardly towards an outlet 34. The gas and air mixture is supplied at 35 to the mixture chamber 36 of the burner. The bottom of the double walled chamber is further provided with apertures 35 for the entrance of combustion air into the space 33. The burner table 38, which extends 55 into the mixture chamber 36 with an extension 60 39, may be removed and replaced through an opening 40, adapted to be closed.

It will be clear that an individual element such as described has the advantage that in a simple manner a hot water radiator of any 65 desired heat capacity may be composed by

connecting the said elements at either side to one radiator element or two elements, three elements, etc.

Finally it is remarked that a hot water radiator according to the invention may, if desired, also be built in in an ordinary central heating system. It may operate with gas heating as an independent radiator and is then temporarily cut off from the circulation of the central heating system or it may operate as an ordinary radiator without gas heating and is then inserted in the circulation of the central heating system.

I claim:-

1. A hot water system, comprising two groups of radiator elements, connecting members between the lower ends and between the upper ends of said elements, a double-walled water heating container located between the groups of radiator elements and connected to the upper and lower connecting members, and a burner below the container, the body of the burner having a water jacket connected to the radiator elements.

2. A hot water system as set forth in claim 1, including a water storage tank, a conduit between the upper connecting member and the water storage tank, an expansion tube in the water tank, whereby steam from the upper connecting member may escape through the expansion tube to said tank, and a conduit from the bottom of the water storage tank to the lower connecting member, whereby water from the storage tank may replenish the circulating water.

In testimony whereof I affix my signature.
ANTONI WILHELM KRUL.
